Application August 27, 1941, Serial No. 408,410

5 Claims. (Cl. 184—3)

1

The invention relates in general to railroad track equipment and, more particularly, to devices for lubricating the flanges of car wheels and the flange engaging surfaces of the rails. The invention further relates to operating mechanism which, when actuated by the passage of rolling stock, supplies lubricant quickly and efficiently.

According to a preferred embodiment of the invention, a ramp assembly is mounted upon a running rail and a hydraulic tank having a hydraulic pump is operatively connected to the ramp assembly. Spaced from the track structure and independently mounted on the road bed is a reservoir and lubricant supply mechanism. The reservoir may comprise a comparatively large tank set in the ground in which is disposed a lubricant pumping unit or gun having suitable driving devices driven by the hydraulic pump through suitable pumping connections. The pumping unit or gun may comprise an aligned double-acting hydraulic motor and pump, and suitable connections may be provided from the discharge of the lubricant pump to the actual lubricant applying device associated with the track for applying lubricant to the wheel flanges.

The ramp may be provided with ramp springs for holding it in the path of the rolling stock and its connection with the hydraulic pump is preferably such that the pumping action occurs with upward movement of the ramp under influence of the ramp springs, the hydraulic pump being a single acting pump and exerting no pumping action with downward movement of the ramp. If desired, however, the connections may be reversed so that the pumping stroke occurs with downward movement of the ramp in which case a suitable maximum pressure or relief valve may be provided in the discharge of the pump within the hydraulic tank to release the hydraulic fluid in the event a serious stoppage occurs either in the hydraulic or lubricant lines.

If desired, instead of filling the lubricant reservoir with lubricant by transferring from a shipping container, provision may be made for utilizing the shipping container itself as a part of the reservoir. In this case, a suitable foundation or container will be provided to receive the shipping container and the power driven pump unit or gun will be mounted upon a suitable removable support so that this assembly may be removed from the shipping container when the lubricant is consumed and then replaced when a full shipping container is substituted.

The invention also consists in certain new and original features of construction and combina-

2

tions of parts hereinafter set forth and claimed.

Although the novel features which are believed to be characteristic of this invention will be particularly pointed out in the claims appended here-to, the invention itself, as to its objects and advantages, and the manner in which it may be carried out, may be better understood by referring to the following description taken in connection with the accompanying drawings forming a part thereof, in which

Fig. 1 is a plan view of one running rail with the invention applied thereto.

Fig. 2 is a section on the line 2—2 of Fig. 1.

Fig. 3 is an enlarged section taken on the line 15 3—3 of Fig. 1 and showing the ramp and hydraulic pump assembly.

Fig. 4 is a section on the line 4—4 of Fig. 1 showing the ramp assembly without the hydraulic pump unit.

20 Fig. 5 is a section on the line 5—5 of Fig. 3.

Fig. 6 is an enlarged section on the lines 6—6 of Figs. 3 and 4.

Fig. 7 is a plan section taken on the line 7—7 of Fig. 3.

25 Fig. 8 is a section through the lubricant reservoir.

Fig. 9 is a longitudinal section through the lubricant or grease gun.

Fig. 10 is a section on the line 10—10 of Fig. 9.

30 Fig. 11 is a transverse section taken on the line 11—11 of Fig. 10.

Fig. 12 is a section through a modified form of lubricant reservoir, using the removable shipping container; and

35 Fig. 13 is a side elevation of a modified structure corresponding to Fig. 3 but having the pumping stroke of the hydraulic pump occur with downward movement of the ramp.

In the following description and in the claims, 40 various details will be identified by specific names for convenience, but they are intended to be as generic in their application as the art will permit.

Like reference characters denote like parts in the several figures of the drawings.

45 In the drawings accompanying and forming part of this specification, certain specific disclosure of the invention is made for purposes of explanation, but it will be understood that the details may be modified in various respects without departure from the broad aspect of the invention.

Referring now to the drawings, and more particularly to Figs. 1 and 2, the running rail is denoted by 10 and the usual supporting ties by 11. Secured to the running rail is a delivery plate 55 12 having a grease applying slot 13 for supplying

lubricant to the outer surfaces of the flanges of the wheels running on the rail 10. Also secured to the track structure is a ramp 14 driving a hydraulic pump 15 which is connected to a hydraulically driven gun 16 located in the reservoir 17 alongside the track. The reservoir 17 contains lubricant and the gun 16 draws lubricant from the reservoir and discharges it through a pipe system indicated by 18 to the delivery device 12. Hydraulic pipes 19 and 20 having flexible sections connect the hydraulic pump 15 and the grease gun 16.

The lubricant applying apparatus, of which delivery plate 12 forms a part, is fully disclosed and claimed in Heidenthal patents, No. 2,059,235 granted November 3, 1936, and No. 2,185,810 granted January 2, 1940, to which reference is made for a more complete disclosure. It is sufficient for present purposes to refer to Fig. 5 of the present application where it will be noted that the head 23 of the rail 10 is cut away to put the delivery slot 13 at the proper location for applying streaks of lubricant to the wheel flanges. A series of branch conduits 24 are located along the length of the rail and supply lubricant to the delivery plate 12 uniformly and evenly by the system of piping indicated in general by 18.

It will be understood that the wheels rolling along the running rail 10 operate the ramp 14, which in turn reciprocates the hydraulic pump 15 which sends hydraulic fluid, such as light oil, through discharge pipe 19 to the grease gun 16, the return hydraulic fluid returning through pipe 20 to the tank 45. The gun 16 draws lubricant, which may be a heavier grease, from the bottom of reservoir 17, delivering it through the system of piping 18 as above described.

Referring now to the ramp assembly, shown more particularly in Figs. 3 to 7, this comprises a filler plate 28 and a housing plate 29 suitably bolted to the running rail 10. The ramp 14 is located between the housing plate 29 and the rail head 23 and is pivoted at one end by a pivot bolt 27. The filler and housing plates 28 and 29 have suitable recesses 30 forming seats for helical springs 31, which engage the lower surface of the ramp 14 urging it upward. The top surface of the ramp 14 is suitably cammed or beveled to accommodate traffic in both directions.

For adjusting the height of the ramp a stud bolt 32 is passed through the filler plate 28 and rail 10 and is located within a recess formed by a strap 33 secured to the underside of the ramp 14. Located in this recess is a master shim 35 and a plurality of adjusting shims 36 held in position, on the one side by the surface of filler plate 28 and on the other side by a cover plate 37 held in position by a cotter pin 38 passing through stud 32. Thus, by taking out or adding shims 36 the uppermost position of ramp 14 may be adjusted and the corresponding stroke applied to the hydraulic pump also adjusted.

Secured to the housing plate 29 is the hydraulic tank body 45, which comprises a rectangular box having a removable cover 46. The tank body has an extension 48 through which passes bolt 44 which also passes through the housing plate 29, filler plate 28, rail 10 and delivery plate 12. Extension 48 has a shoulder 42 engaging housing plate 29. Other bolts 47 secure the tank 45 to the housing plate 29. Bolt 39 also completely passes through the housing plate, filler plate, rail, and delivery plate. Top cover 46 is provided with a removable supply plug 57 having a vent opening as indicated in Fig. 6.

The hydraulic pump 15 is set in the side wall of tank 45, as shown more particularly in Fig. 7, and comprises a cylinder 53 connected to a plate 58 having a suitable stuffing box 51 for the piston rod 59. It will be understood that the plate 58 is of square configuration and is suitably secured to the wall of tank 45 by suitable bolts indicated by 43 in Fig. 3.

Secured to piston rod 59 is the piston 49 which reciprocates within the cylinder 50, the latter being provided with an inlet check valve 52 and a discharge check valve 53 which communicates with the discharge pipe 54 passing through the wall of tank 45 and connecting with the discharge pipe 13. The return pipe 20 also passes through the wall of tank 45 and has a standing end indicated by 56 located above the level of the hydraulic fluid indicated by 55 in Fig. 6 to prevent loss of oil should pipe 20 break.

It will be understood by those skilled in the art that as the piston 49 in Fig. 7 moves to the left the liquid will be drawn in through the inlet valve 52, and as the piston 49 moves to the right the inlet valve 52 will be closed and the discharge valve 53 will open, discharging liquid under pressure through pipes 54 and 19.

The connections for driving the hydraulic pump 15 by the ramp 14 will be understood from the following description taken with Figs. 3, 4 and 5 of the drawings. Bolted to the web of the rail 10 is a Z plate 62, the bolt being indicated by 63. Additional bolts indicated by 64 pass through plate 62 into filler plate 28. The end of plate 62 projects away from the filler plate 28 and a short shaft 65 passes therethrough. On one end of the shaft 65 is an inner arm 66 and on the other end is an outer arm 60. Link 61 is suitably pivoted to the end of ramp 14 and to the end of arm 66. Another link 75 is pivotally connected to arm 60 and to a fitting 76 secured to piston rod 59.

Referring now more particularly to Figs. 9 to 11, the power driven grease gun will now be described. This gun may be purchased on the market and forms no part of the present invention, except as it is combined with the elements used therewith to provide the present track lubricator.

The gun 16 comprises an upper head 80 and a lower head 81, having upper cylinder 82 clamped thereto by three bolt and nut assemblies 83. Secured to the lower end of fitting 81 is a lower cylinder 84, having an intake valve cap 85 supporting a valve disk 86 and a strainer 87. Lugs 88 are for the purpose of spacing the gun on the bottom of the reservoir tank 17 to permit lubricant to be drawn in through strainer 87. Located within the lower cylinder 84 is an intermediate cylinder 89 providing an annular space connecting with duct 94 communicating with the discharge pipe 167.

Located within the upper cylinder 82 is an upper piston 90 formed of two disks 91 and 92 suitably bolted together and holding rings of packing 93. Located within the intermediate cylinder 89 is the intermediate piston 100, made up of upper section 101 and a lower section 102 suitably screw threaded together to hold packings 103. A hollow piston rod 104 connects pistons 90 and 100.

Located within the lower cylinder 84 is a lower piston 105 made up of sections 106 and 107 threaded together to clamp packing 108 therebetween. Rod 109 threaded into section 102 of piston 100 is provided with a nut 110 clamping a collar 111. Cap 112 is threaded on section 106 to secure piston rod 109 thereto. Sections 106 and

107 are provided with passages communicating both above and below the packing 108, and section 107 is provided with a seat 115 against which is positioned a ball 113 held in position by spring 114.

The upper head 80 contains the valve mechanism for alternately supplying fluid pressure above and below the piston 90 to make this piston and its cylinder in effect a double acting hydraulic motor. A plate 120 is threaded into the end of casing 89, forming the end wall of cylinder 82. Passing through end wall 120 and through hollow piston rod 104 is a valve stem 121 having abutments 122 and 123.

Located on the upper end of valve stem 121 are collars 124 and 125, and surrounding the stem 121 is a spring 126 engaging an upper collar 127 loosely mounted on the valve stem 121 and engaging a ring 129 fixed to detent sleeve 131. Spring 126 also engages a collar 128 which engages both an abutment on spindle 121 and an abutment on detent sleeve 131.

The detent sleeve 131 is provided with annular grooves 132 and 133 adapted to selectively engage with both detents 134 held in position by springs 135 backed by caps 136. Loosely connected to the detent sleeve 131 by a screw and slot connection 138 is the slide valve 137, which slides within a liner or sleeve 139 provided with a series of holes. These holes line up with corresponding openings in a series of rings 140, 141 and 142 held in position by sleeve 143 and cap 144 by suitable bolts 145 passing through the cap into the body of the head 80. The rings 140, 141 and 142 surround the liner 139 and hold it down against the cylinder head 120.

The openings in the upper ring 140 communicate with passages 150, Fig. 10, leading to the upper end of cylinder 82. The openings in intermediate ring 141 connect with inlet duct 151 to which supply pipe 19 is connected. The openings in the lower ring 142 connect with passage 152, pipe 153, passage 154, leading to the lower end of cylinder 82. The sleeve liner 139 has exhaust holes 158 at its lower end communicating with annular space 159, to which exhaust pipe 20 is connected. Pipe 20 also connects with passages 148 and 147 to the space above liner 139.

A brief description of the operation of the gun 16 will now be given. In the positions shown in Figs. 9-11, the several pistons 90, 100 and 105, are each at the top of their strokes and the downward stroke is about to begin. Hydraulic fluid under pressure from pipe 19 passes through passage 151, the openings in ring 141 and the adjacent openings in liner 139 through the annular port 146 of slide valve 137, thence through openings in liner 139 and corresponding openings in ring 140, thence into communication with the ducts 158, Fig. 10, communicating with the space above motor piston 90. Piston 90 is then forced downwardly, driving pistons 100 and 105. The space in cylinder 84 below lower piston 105 having previously been filled with lubricant due to the previous upward stroke of piston 105, this lubricant now opens check valve 113 passing to the space above piston 105. Check valve 86 prevents this lubricant from being expelled back into the reservoir. The downward movement of intermediate piston 100 thus decreases the volume of the combined space defined by cylinders 84 and 89, forcing lubricant up between these two cylinders into the annular space 94 and cut through the discharge pipe 167 as indicated by the arrow.

As the motor piston 90 approaches the bottom

of its stroke it engages shoulder 122 on valve stem 121 which carries this stem downwardly together with sleeve 124 and collar 127, compressing spring 126 until sleeve 125 engages collar 128 which carries detent sleeve 131 downward. Downward movement of sleeve 131 causes spring pressed balls 134 to disengage groove 133 and engage in groove 132 with a snap action, thus carrying sleeve valve 137 from the position shown in Figs. 9 and 10 to a position where valve port 146 connects the openings in liner 139 corresponding to the openings in rings 141 and 142.

This connects the hydraulic supply pipe 19 through duct 151, the openings in rings 141 and 142 and corresponding openings in the liner 139 to duct 152, pipe 153 and duct 154, thus supplying pressure to the cylinder 16 under piston 90 which causes the upward movement of the pistons. The space above piston 90 communicates with the discharge pipe 20 to exhaust the hydraulic fluid admitted for the downward stroke, through ducts 150, Fig. 10, the openings in ring 140 and corresponding openings in liner 139 to the space above slide valve 137, thence outwardly through ducts 147 and 148 to exhaust pipe 20.

The upward movement of lower piston 105 forces lubricant above it into intermediate cylinder 89 and also the space between cylinders 89 and 84, but since piston 105 is larger than piston 100 more lubricant is moved upwardly by piston 105 than the corresponding displacement of piston 100 and the difference is expelled through annular channel 94 and discharge pipe 167.

The upward movement of lower piston 105 also tends to create a vacuum in cylinder 84 under the piston which opens check valve 86, drawing in lubricant through strainer 87.

As the piston 90 approaches the upper end of its stroke, the piston 100 engages the abutment 123 on the lower end of valve stem 121, which moves collar 128 upwardly, compressing spring 126 until collar 125 engages collar 127, which engages ring 129 to move detent sleeve 131 upwardly to cause detents 134 to snap from groove 132 to groove 133, the position shown in these figures.

The upward movement of detent sleeve 131 carries slide valve 137 with it, moving it to the position shown, connecting the hydraulic supply pipe 19 to the space above piston 90 as above described and communicating the space below piston 90 through duct 154, pipe 153, duct 152, the openings in ring 142, corresponding openings in liner 139 and the openings 158, annular space 159, with the hydraulic discharge pipe 20.

Thus we have a double acting power driven lubricant pump or gun, which delivers a constant stream of lubricant to discharge pipe 167 with both downward and upward strokes of the pistons. 60 This insures the constant supply of lubricant to the track so long as pressure is supplied to hydraulic feed pipe 19.

Referring now to Figs. 1, 2 and 8, the reservoir 17 comprises a large tank 160 of ample size to hold a considerable quantity of lubricant, set in the ground alongside the road bed spaced somewhat from the rails and ties so as to be free from movement imparted to the track by movement of the rolling stock. The tank 160 may have a two part cover, one part 161 being fixedly secured to the body 160 and the other part 162 having a hinged connection 172 with part 161. Hinged lid 162 may be provided with an apertured ear or lug 171 at

75 operating with an apertured ear or lug 171 at

tached to the body 160 for the reception of a padlock or the like.

Suitable provision may be made for excluding water and to this end the members 161 and 162 may have a peripheral flange 173 and the joint between parts 161 and 162 may have a seal comprising a rib or flange 170, over which is disposed a bead 163 on the lid 162.

The gun 16 may be mounted on a suitable bracket 165 secured to the walls of body 160 as by suitable bolts passing through the bracket into the flange 166 of the lower head 81. The discharge pipe 167 may have incorporated therein a relief valve 168 for purpose of relieving excess pressure in pipe 167, the relief valve 168 then diverting the grease back into the reservoir 17. Discharge pipe 167 connects, by a suitable flexible connection 169, with the net work 18 supplying the various portions of the lubricant applying device 12. The discharge pipe 167 together with hydraulic pipes 19 and 20 may pass through a suitable plate 174 detachably or otherwise secured around an opening in the side wall of body 160.

It will thus be seen that as trains move over the running rail 10, the ramp 14 will be reciprocated up and down, downward movement being caused by the weight of the trains and the upward movement being caused by the ramp springs 31. The downward movement of the ramp 14 causes a retracting movement to piston 49 of the hydraulic pump 15, drawing hydraulic fluid from the tank 45 into the cylinder. The upward movement of the ramp 14 under the influence of springs 31 applies the pumping force to piston 49 of the single acting hydraulic pump, discharging hydraulic fluid through the discharge pipe 19 to the hydraulic gun 16, which pumps lubricant to the track as above described. The exhaust fluid returns through pipe 20 to tank 45, where it discharges above the normal liquid level in tank 45. Thus, the force applying the pumping action is limited to the strength of the springs 31, which are so designed as to maintain all forces below the rupture point of all of the hydraulic and lubricant apparatus concerned should a stoppage occur anywhere. Thus, if desired, the excess pressure valve 168 in the lubricant line may be omitted.

The successive reciprocations of the hydraulic pump due to the passage of successive wheels of rolling stock impart comparatively small successive spurts of hydraulic pressure to the gun 16, which in turn causes the lubricant to be fed evenly and uniformly. As soon as the last wheel has passed, the hydraulic pressure is immediately terminated and the gun 16 immediately stops feeding, there being no large quantity of lubricant under pressure to continue to feed after the hydraulic driving impulses have been terminated. Thus there is no danger of flooding or over-supplying the delivery or applying apparatus 12. On the other hand, the check valve 53 insures hydraulic pressure being always maintained in the hydraulic supply pipe 19, and upon the passage of the first pair of wheels of a train, hydraulic pressure is built up immediately and lubricant will be supplied to the delivery slots 13 immediately.

In some cases it may be desirable to have the downward movement of the ramp 14 impart the power stroke to the hydraulic pump and the ramp springs impart the retracting movement. The invention conveniently adapts itself to this modification as illustrated particularly in Fig. 13. Here corresponding parts are denoted by the

same reference characters followed by the letter *a*, the ramp being indicated by 14*a*, the pivoted stud shaft by 65*a*, the arms connected thereto by 60*a* and 66*a* and the connecting links by 61*a* and 75*a*. The hydraulic pump 15*a* is of the same construction as the pump 15 and supplies discharge pipe 54*a* which is connected in substantially the same manner with the gun as discharge pipe 54. However, interposed in pipe 54 is an excess pressure valve or safety valve 176 which relieves any excess hydraulic pressure, diverting the excess liquid back into the tank 45*a* in the event defects occur in any part of the apparatus causing excess pressures to be built up. The relief valve 176 is necessary here in view of the weight of the rolling stock being sufficient to impart forces to the apparatus sufficiently high to cause breakage in the event some stoppage or other defect occurs. The advantage of this modification is that hydraulic pressure is obtained a little bit more quickly than with the type first described in that the first downward movement of the ramp supplies the hydraulic pressure, whereas in the form first described hydraulic pressure is not built up until upward movement of the ramp occurs.

In some cases it is desirable to utilize the original shipping containers for the lubricant as the reservoir. This procedure eliminates the transfer of the lubricant from the shipping container to the reservoir when it is necessary to replenish the supply. This bodily transfer of lubricant from one container to another is not only a nuisance but is hazardous in that the workmen are sometimes careless and get foreign matter into the lubricant which interferes with the operation of the track lubricator.

To this end the arrangement of Fig. 12 is provided, this being illustrated somewhat diagrammatically. This form comprises a holder or foundation 177 permanently set in the ground alongside of the track and spaced from the track and independent of movement thereof. The shipping container which is indicated by 178 may be in the form of a metal drum, having a top 179 provided with an opening normally closed by a removable lid (not shown). When this lid is removed, a housing 180 may be put in its place, this housing having a hinged lid 182. The housing may have a depending annular lip fitting within the opening in the top 179 and suitable provision made to keep water from getting into the lubricant.

For supporting gun 16*b* the housing 180 may have a plate 183 connected thereto having a suitable opening through which the gun will be disposed. The gun is provided with a plate 184 welded or otherwise secured thereto for engaging the plate 183. The discharge pipe 167*b* may have a relief valve 168*b* and both the pipe 167*b* and hydraulic pipes 19*b* and 20*b* may have detachable couplings 185, 186 and 187 for the purpose of disconnecting these pipes.

When the grease in the shipping container 178 is exhausted, it is only necessary to detach the couplings 185, 186 and 187 and bodily remove the housing 180 and gun 16*b*. The empty container 178 is then removed from the holder 177 and a full container 178 substituted, after which the housing 180 and gun 16*b* will be replaced in the position shown. After the couplings 185, 186 and 187 are tightened the apparatus is ready for use.

Thus a hydraulic track lubricator has been described which is simple and efficient in opera-

tion. It is easy to install since both hydraulic pipes and lubricant pipes have flexible sections so that it is not necessary to line up the reservoir and lubricant gun with the apparatus on the track structure. Mechanical reciprocating parts and resulting lost movement is reduced to a minimum and a single positive pumping unit is provided.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a track lubricator, a track structure, a lubricant applying device associated therewith for applying lubricant to wheels running on said track structure, a ramp pivoted to said track structure to be operated by passage of rolling stock, a ramp housing partially enclosing said ramp, a hydraulic tank secured to said ramp housing, a hydraulic pump mounted in said tank and connected to said ramp, a lubricant reservoir mounted alongside the track independently thereof and spaced therefrom, a lubricant gun in said reservoir comprising a double acting hydraulic motor driving a double acting lubricant pump, said pump receiving lubricant from said reservoir, flexible means for delivering lubricant from said pump to said applying device, and flexible hydraulic supply and return pipes connecting said hydraulic pump and said hydraulic motor.

2. In a rail lubricator, a track structure, a ramp pivoted thereto, a housing partially enclosing said ramp, a hydraulic tank secured to said housing, a reciprocating, single acting hydraulic pump having a cylinder projecting from a side wall of said tank, said cylinder containing a piston having a piston rod projecting out of said tank, drive connections from said ramp to said rod, said cylinder having an inlet check valve communicating with hydraulic liquid in said tank and an outlet check valve, said cylinder being immersed in said liquid, a discharge pipe connecting said outlet valve and passing through the wall of said tank, a return pipe passing through the wall of said tank and extending above the highest liquid level therein, a lubricant supplying device comprising a double acting hydraulic motor connected to a lubricant pump, both said pipes being connected to said hydraulic motor to circulate hydraulic fluid through said hydraulic pump and motor in a closed circuit to cause said lubricant pump to supply said track structure with lubricant.

3. In a track structure, a running rail having a lubricant applying device associated therewith, a ramp assembly comprising a filler plate secured to the web of said rail, a housing plate secured to said rail and a ramp pivoted to said rail and mounted between the head of said rail and said

housing plate, a hydraulic tank secured to said housing plate, a pump in said hydraulic tank, drive connections between said ramp and said pump, a lubricant reservoir spaced from said rail said reservoir being mounted alongside the track and independent of movement thereof, hydraulic lubricant supplying device in said reservoir, a flexible conduit connecting said supplying device and said applying device, and flexible hydraulic conduits between said hydraulic pump and said hydraulic lubricant supplying device.

4. In a rail lubricator, a track structure including a running rail, a lubricant applying device on said track structure for applying lubricant to wheels running on said running rail, a hydraulic pump forming part of said track structure and having an actuating member operated by the passage of rolling stock, a lubricant reservoir mounted alongside of the track structure so as to be independent of movement of said track structure caused by passage of rolling stock, a lubricant gun comprising a double-acting, reciprocating lubricant pump and a double-acting, reciprocating hydraulic motor, said lubricant pump including a cylinder with a piston working therein, said hydraulic motor also including a cylinder with a piston working therein, said gun being vertically disposed in said reservoir with the cylinders of its pump and motor in line and their pistons direct-connected and with the hydraulic motor above the lubricant pump, a flexible conduit extending from said lubricant pump to said lubricant applying device, and flexible hydraulic conduits between said hydraulic pump and said hydraulic motor.

5. In a rail lubricator, a track structure including a running rail, a lubricant applying device on said track structure for applying lubricant to wheels running on said running rail, a hydraulic pump, means operating said hydraulic pump by passage of rolling stock moving over said running rail, a lubricant reservoir containing lubricant, a lubricant gun comprising a double-acting reciprocating hydraulic motor direct connected to a double-acting reciprocating lubricant pump, hydraulic connections between said hydraulic pump and said double-acting hydraulic motor, said hydraulic pump and hydraulic motor having such relative displacement that a plurality of double strokes imparted to said hydraulic pump is required to complete the stroke of said hydraulic motor in a single direction, said motor having direction reversing devices to reverse the direction of motion of said motor when it reaches either end of its stroke, said lubricant pump having communication with said reservoir to draw in lubricant on each stroke in each direction, said lubricant pump also having communication with said lubricant applying device to deliver lubricant thereto on each stroke in each direction.

ALBERT F. HUBER.
